[57] CLAIM

The ornamental design for a toy bus, substantially shown and described.

DESCRIPTION

FIG. 1 is a top plan view of a toy bus showing our new design;

FIG. 2 is a right side elevational view thereof; FIG. 3 is a bottom plan view thereof;

FIG. 4 is a front elevational view thereof; and FIG. 5 is a rear elevational view thereof.

The side of the toy bus opposite the view of FIG. 2 is substantially a mirror image thereof.

FIG. 1

FIG. 2

FIG. 3

FIG. 5

FIG. 4
